WINDOW FASTENER

Carl E. Olson, Minneapolis, Minn.

Application March 25, 1948, Serial No. 16,987

2 Claims. (Cl. 292—194)

1
My invention relates to an improvement in a window fastener wherein it is desired to provide a simple device for attaching a window or the like in place in its frame.

Various devices have been used for holding a window sash in place within its frame. Such devices are commonly used for holding screens and storm windows in window frames so that they may be removed and interchanged when desired. The present device is intended for the same purpose and is designed to hold the window in place under spring tension.

It is the object of the present invention to provide a window fastener comprising three parts, two of which are permanently attached in place and the other of which is pivotally secured to one of the fixed parts. The pivotal part is provided with an integral sleeve designed to extend through an aperture in the other part. The entire device may be assembled by merely inserting the sleeve of the pivotal part into the aperture of a fixed part and riveting the sleeve end to hold the two parts assembled.

A feature of the present invention lies in the fact that one of the permanently attached parts forms a base upon which the pivotal part may rotate so that the pivotal part does not scrape over the surface of either the window or its frame to destroy the coating of paint thereupon. Most window fasteners designed to accomplish a similar purpose frictionally engage the window and if these parts tightly anchor the window they are apt to scrape the paint therefrom, allowing moisture to penetrate into the wood to rot the wood. Furthermore if the window frame is formed of metal the scraping of a pivotal part over the surface often destroys the protective surface of the metal and causes the same to rust or oxidize.

An added feature of the present invention lies in the provision of a pivotal part equipped with a slot extending in a generally radial direction from the center of rotation. This slot is designed to accommodate the end of a screw driver or similar tool by means of which the fastener may be rotated. Because of the requirement of some type of tool to rotate the pivotal part of the fastener, the fastener is not likely to become accidentally disengaged.

An added feature of the present invention lies in the provision of a fastener having a rotatable part which is engageable with a keeper shaped to provide a cam action. This keeper is provided with flared ends which permit relatively easy engagement of the rotary part therewith. However, the keeper tends to urge the rotary part inward-

ly upon rotation thereof, urging the storm window against its frame under spring tension.

An added feature of the present invention lies in providing a rotary part engageable with a cam shaped keeper and in providing a base plate over which the rotary part rotates. This base plate is provided with a projecting ear which underlies the rotary part in engaged position thereof so as to support the rotary part and prevent bending thereof.

These and other objects and novel features of my invention will be more clearly and fully set forth in the following specification and claims.

In the drawings forming a part of my specification:

Figure 1 is an elevation view of my window fastener showing the construction thereof.

Figure 2 is a view similar to Figure 1 showing the fastener in disengaged position.

Figure 3 is a sectional view through a portion of the window sash and frame.

Figure 4 is an elevation view of the keeper showing the construction thereof.

Figure 5 is a sectional view through the fastener and its base plate, showing the manner in which the two parts are rotatably connected.

Figure 6 is a plan view of a modified form of window fastener.

Figure 7 is a sectional view of the fastener illustrated in Figure 6, the position of the section being indicated by the line 7—7 of Figure 6.

The window fastener A illustrated in the drawings is designed to connect a window sash such as B to its frame such as C. In speaking of the element B as a window sash, it should be understood that this element may comprise a shutter, screen, or other panel. Furthermore, it is obvious that the parts of the structure may be reversed if desired from the positions illustrated. However, for the purpose of simplicity the element B will be described as a window sash and the element C will be described as its frame. The fastener A includes a base plate 10 having a rotatable latch part 11 rotatably connected thereto. The base plate 10 is illustrated as being generally oval in shape and is provided with spaced apertures 12 near opposite ends thereof for accommodation of anchoring screws or bolts 13. As illustrated in Figure 2, the base plate 10 is provided with an ear 14 projecting laterally therefrom near its minor axis so as to extend beneath the rotary part 11 in engaged position of this rotary part as will be later described in detail.

The base plate 10 is provided with a central aperture 15 therethrough which may be counter-

3

sunk as indicated at 16 in Figure 5 of the drawings. The countersunk portion of the hole is on the under or base surface of the base plate 10 and opposite the surface over which the rotary part 11 is designed to rotate.

The rotary part 11 comprises a body having an arcuate portion 17 extending throughout more than 180 degrees about its center and a blunt pointed projecting end 19 projects therefrom. A sleeve 20 is punched from the axis of the rounded portion 17, the axis of the sleeve being normal to the plane of the rotary part. This sleeve 20 is of proper outside diameter to fit within the aperture 15 in the base plate 10. The extremity 21 of the sleeve 20 is riveted over into the counter-sunk portion 16 of the base plate so as to permanently attach the rotary part 11 to the base plate 10.

In actual practice the construction described is simple to manufacture and assemble. The sleeve 20 is merely punched from the body of the plate and is drawn into a cylindrical hollow shank projecting a short distance from the center of the rotary part. By merely extending this sleeve through the aperture and placing the sleeve beneath a spinning tool, the sleeve end may be flared outwardly as indicated in Figure 5, thereby riveting the rotary part to the base plate by allowing sufficient play to permit relative rotation between these parts.

The keeper is indicated in general by the numeral 22. This keeper includes a base portion 23 comprising an elongated strip of metal or the like having punched or pressed therefrom a rounded off-set portion 24. The off-set portion 24 is rounded in its periphery and the rounded portion is of slightly greater radius than the pointed end 19 of the rotary part 11. Thus when properly placed relative to the rotary part 11, the off-set portion 24 will be concentric therewith and will enclose the blunt pointed end 19 of this rotary body.

As indicated in Figure 4 of the drawings the off-set portion 24 is provided with a downwardly rounded forward edge, the center portion 25 of this forward edge being below the level of the end portions thereof. As a result of this construction the pointed end 19 of the rotary part 11 can readily enter the off-set portion at the ends thereof, but as this pointed portion is pivoted toward the center of the off-set, additional pressure is exerted against the rotary part. The projecting point 14 on the base plate 10 supports the rotary part 11 beneath the pointed end 19 as this pointed end is urged rearwardly by the cam shape of the off-set portion 24.

A radially extending slot 26 is provided in the rotary part 11 designed to accommodate the end of a screw driver or similar tool. By inserting the screw driver into this slot and properly manipulating the same, the rotary portion 11 may be rotated about its axis for engagement or disengagement with the keeper 22.

As indicated in the drawings the keeper 22 is provided with spaced apertures 27 at opposite ends of the base plate 23 for accommodation of fastening screws 29 by means of which the keeper plate may be attached in place.

The fastener is extremely simple in construction and holds the window firmly in place under spring tension due to the action of the cam shaped off-set 24 bearing against the rotary part 11. There is sufficient resilience in the keeper to urge the window tightly against its frame. Due to the fact that a screw driver or similar in-

strument is used for rotating the fastener, the fastener will not become accidentally disengaged as readily as will turn buttons or other devices previously used. Furthermore, the rotary part 11 is spaced from contact both with the window and the frame and thus will not affect the surfaces of these elements in operation.

In Figures 6 and 7 of the drawings I disclose a modified form of fastener which is indicated in general by the letter D. This fastener is identical in operation to the fastener previously described, but is somewhat simpler to manufacture and attach. Only one part of the fastener is illustrated in Figures 6 and 7 as the keeper 22 is used with the fastener in the manner previously described.

The fastener D includes a base plate 30 which is provided with an integral sleeve 31 at its center point. The sleeve 31 is punched from the body of the plate 30 into tubular form and forms a means of connecting the base plate with the rotatable latch plate 32.

The base plate 30 is generally circular in shape and is provided with an ear 33 projecting from one side thereof. The ear 33 is designed to extend toward the adjacent edge of the window so as to form the longest possible bearing for the latch plate 32. The latch plate 32 is provided with a rounded edge 34 having a pointed end 35 projecting to one side thereof. An elongated slot 36 extends radially through the plate 32 directed toward the pointed end 35 thereof.

The base plate 30 is provided with a pair of spaced downwardly extending prongs or lugs 37 which extend into the surface of the window or other element on which the base plate is mounted to prevent this base plate from rotating. The upper end of the sleeve 31 is riveted over the beveled outer end 39 of an aperture 40 through the latch plate 32. The sleeve 31 thus holds the latch plate assembled to the base plate and allows rotation of the latch plate relative to the base plate.

The sleeve 31 is hollow to admit a headed screw or similar fastening means used to hold the window fastener in place.

From the foregoing description it will be obvious that the fastener D differs from the fastener A mainly in the manner in which the base plate is connected to the window. In place of extending the base plate and providing spaced screws to hold the same in place the fastener D employs a single screw which extends through the central sleeve and depends upon the prongs 37 for holding the base plate from rotation.

In accordance with the patent statutes, I have described the principles of construction and operation of my window fastener, and while I have endeavored to set forth the best embodiment thereof, I desire to have it understood that obvious changes may be made within the scope of the following claims without departing from the spirit of my invention.

I claim:

1. A fastener for holding a window element to its frame element comprising a flat base plate part adapted to be secured to one of said elements near an edge thereof, and a flat rotary part having a projecting ear portion, means pivotally connecting said two parts together for rotation of said rotary part on a single axis over said base plate part, said rotary part being provided with a narrow elongated radially extending aperture spaced from the axis thereof for accommodation of a tool for rotating the rotary part, said elongated aperture guiding the tool about said single axis, and said base plate part being

of such dimensions to at least partially underlie said elongated aperture throughout its travel.

2. A fastener for holding a window element to its frame element comprising a flat base plate part adapted to be secured to one of said elements near an edge thereof, and a flat rotary part having a projecting ear portion, means pivotally connecting said two parts together for rotation of said rotary part on a single axis over said base plate part, said rotary part being provided with a narrow elongated radially extending aperture spaced from the axis thereof for accommodation of a tool for rotating the rotary part, said elongated aperture guiding the tool about said single axis, and said base plate part being of such dimensions to at least partially underlie said elongated aperture throughout its travel, said base plate part having a flat ear adapted to underlie said projecting ear portion when said projecting ear portion and said ear are in 20 radial alignment to provide a bearing for said rotary part.

CARL E. OLSON.
